LOCOMOTIVE AND CAR WHEEL GRINDING MACHINE

James G. Julian and Fred A. Daniels, Sr.
Columbia, S. C.

Application September 20, 1949, Serial No. 116,716

5 Claims. (Cl. 51—104)

1

This invention relates to an improved machine for grinding the worn wheels of locomotives and cars, the primary object of the invention being to provide a more efficient and reliable machine of this character either in a portable form suitable for grinding such wheels without removing them from the locomotives or cars, or in a stationary form suitable for grinding such wheels while removed from the locomotives or cars.

Another important object of the invention is to provide a machine of the character indicated above capable of grinding a pair of wheels at a time on opposite sides of a locomotive or car.

Other important objects and advantageous features of the invention will be apparent from the following description and the accompanying drawings, wherein, for illustration herein, a specific embodiment of the invention is set forth in detail.

In the drawings:

Figure 1 is an outboard end elevation showing the machine positioned to grind a car wheel;

Figure 2 is a fragmentary side elevation looking from right to left in Figure 1;

Figure 3 is a top plan view of Figures 1 and 2;

Figure 4 is a top plan view of the wheel-elevating means;

Figure 5 is a general schematic top plan view showing the machine arranged to simultaneously grind a pair of the wheels.

Referring in detail to the drawings, wherein like numerals designate like parts throughout the several views, the numerals 6 designate companion rails supported on the ground 7 or other support, above which rails companion car or locomotive wheels 8, 8 are positioned and connected by an axle 9, journaled on a spring bolster 10. The rails 6 are shown with the usual flanges 11 and heads 12.

The illustrated machine, when used without removal of the wheels 8 from a locomotive or car, contemplates the use of wheel cradles 14 which function to elevate the wheels 8 above the rails 6 and to rotate the wheels while being ground. Each cradle 14 comprises a pair of similar, longitudinally-spaced boxes 15 having laterally-spaced depending portions 16 to straddle the related rail, and rest upon the opposite flanges 12 thereof, as indicated in Figure 2, the portions 16 being equipped with set screws 17 to engage the rail web 18 below its head 12. The depending portions have lateral enlargements 19 through which longitudinal bolts 20 extend along opposite sides of the rail 6 and which are equipped with nuts 21 on their opposite ends to draw the boxes 15 to-

ward each other. Laterally-spaced upper portions 22 of the boxes are traversed by axles 23 carrying rollers 24 between the portions 22 to supportably engage the rim of the car wheel 8. One pair of the axles 23 is operatively connected by a shaft 25, as shown in Figure 5, having a pulley 26 thereon over which is trained a belt 27 driven by the electric motor 28, whereby the pair of wheels 8 is rotated together at the same speed.

With the cradles 14 in place with the rollers 24 fore and aft of the wheels 8, the nuts 21 are tightened to bring the rollers closer together and thereby elevate the wheels above the rails so that the wheels can be rotated by the motor 28. Current for operating the motor 28 can be obtained from any suitable source, such as the generator of a Diesel locomotive when the machine is used to grind wheels of such a locomotive.

The motor 28 is mounted on a flat bar 29 laid across the rails 6 and having bolts 30 at its opposite ends operating clamp elements 31 arranged to engage under the outer sides of the rail heads 12, as indicated in Figure 1, to hold the bar 29 in place with the motor belt 27 tight.

The grinding component of the illustrated machine comprises a frame composed of a flat, transversely-elongated bar 32, long enough to extend beyond the outboard sides of the rails 6 when laid thereon, and having pairs of spaced depending lugs 33 to engage opposite sides of the rails, as shown in Figure 2. Each end of the frame bar 32 has a vertical bracket plate 34 extending above and below the bar 32, having bolts 35 and 36 through its upper and lower portions, respectively, which extend through the adjacent side wall 37 of a box-like component 38 having a horizontal top wall 39 and an open bottom. Between the top wall 39 and the lower end of the component 38 is a heavy plate 40 formed in its under side with a concave recess 41, larger in diameter than a large ball bearing 42 which rests in a similar concavity 43 formed in the upper surface of a plate 44 placed upon a supporting block 45 resting upon the rail-supporting surface 7 outside the adjacent rail 6. The thickness of the block 45 is chosen to support the frame bar 32 above the rail head 12. The freedom provided by the ball bearing 42 to roll slightly in any direction or to move universally in the recesses 41 and 43 enables the frame to move relative to the rails 6 by the eccentric motion of out-of-round wheels while being ground without upsetting the accuracy and concentricity of the wheel-grinding action of the machine.

Bolted, as indicated at 46, to the top plate 39 of

2

each frame component 38 is the lower bed plate 47 having a tenon slide portion 48 with which is conformably engaged the similarly-shaped channel 49 of the intermediate or transverse bed plate 50. A traversing screw 51 is arranged through the lower bed plate 47 and engaged in a conventional manner (not shown) with the intermediate bed plate 50, whereby rotation of the handle 52 can move the intermediate bed plate 50 in an inboard or an outboard direction. Similarly keyed on the intermediate bed plate 50 for longitudinal movement at right angles to the intermediate bed plate is the upper bed plate 53. A traversing screw 54 is arranged through the intermediate bed plate 50 and connected to the upper bed plate 53 in a conventional manner (not shown) and the screw 54 has an operating handle 55 for producing movement toward and away from the wheel 8 to be ground.

Bolted on the top of the upper bed plate 53, as indicated at 56, is another and more powerful electric motor 57 whose shaft 58 projects in an inboard direction and has mounted thereon the grinding wheel 59, which, with the motor 57 running, is adapted to be moved across the rim of the wheel 8 in contact therewith by manipulation of the traversing screw handles 52 and 55.

The handles 52 and 55 are manipulated to cause a guide roller 60 on a depending support 61 on the wheel side of the frame component 38 to follow a guide opening 62 in a horizontal guide plate 63 projecting from the same side of the component 38, whereby the face of the wheel 8 will be correctly ground.

Concentricity of the grinding action of the machine with respect to the center of the wheel axle 9 is obtained and maintained by means of a rigid arm 64 projecting upwardly at an acute angle from the lower part of the frame component 38 at the outboard end thereof, as indicated in Figures 1 and 3, and terminating at its upper end in a cylindrical head 65 traversed by a horizontal centering pin 66 on which is threaded a lock nut 66' for engaging the head 65, the centering pin having a point on its inboard end to engage in a hole 68 provided in the end of the wheel axle 9.

With the centering pins 66 engaged in the holes in the ends of the car wheel axle 9 and the wheels 8 supported by the cradles 14 being rotated by the motor 28 and the grinding wheels 59 rotated in engagement with the rims of the wheels, any eccentricity or out-of-roundness of the wheel or wheels will cause the frame of the machine to rock on the ball bearings 42 without losing concentricity with respect to the wheel axle, and the grinding wheels 59 will operate continuously upon the rims of the wheels 8 at the same distance from the centers of the wheels, thereby accurately truing the wheels.

Where existing obstructions around the wheels 8 make desirable the placing of the grinding motor assemblies between the wheels 8 rather than in the outboard relation above described, the intermediate bed plates 50 can be taken off the lower bed plates 47 and placed instead upon an alternate bed plate 70 extending continuously across the frame bar 32 between the rails 6, as shown in Figures 3 and 5, with the motors 57 and grinding wheels 59 in reversed positions, with extensions 71 connected to the transverse traversing screws.

We claim:

1. A machine for grinding locomotive and car wheels comprising a cradle having rollers to en-

gage under spaced portions of the rim of a wheel and support the wheel rotatably thereon, motor means operatively connected to said rollers for rotating the supported wheel, a frame, means mounting said frame on a support for rocking movement conforming to out-of-roundness of the wheel, a motor-driven grinding wheel on said frame, and centering means rigid with said frame having means engageable with the wheel and maintaining axial relation to the wheel whereby said frame is rocked commensurate with out-of-roundness of said wheel and said grinding wheel maintained constantly in contact with the rim of the wheel, said frame-mounting means comprising a support formed with a concavity, a ball bearing resting in said concavity, a frame element having a concave surface resting upon said ball bearing.

2. A machine for grinding locomotive and car wheels comprising a cradle having rollers to engage under spaced portions of the rim of a wheel and support the wheel rotatably thereon, motor means operatively connected to said rollers for rotating the supported wheel, a frame, means mounting said frame on a support for rocking movement conforming to out-of-roundness of the wheel, a motor-driven grinding wheel on said frame, and centering means rigid with said frame having means engageable with the wheel and maintaining axial relation to the wheel whereby said frame is rocked commensurate with out-of-roundness of said wheel and said grinding wheel maintained constantly in contact with the rim of the wheel, said frame comprising means supporting said grinding wheel for movement in a direction across the wheel rim and in a direction toward and away from the wheel rim, a rim-contour guide on said frame, and a guide follower on the last-mentioned means, and means for operating said last-mentioned means in a manner to cause said guide follower to follow said guide so as to determine the rim contour produced on the wheel by said grinding wheels.

3. A machine for simultaneously grinding a pair of car wheels comprising a separate cradle means for supporting each of said wheels above its associated rail, rollers longitudinally spaced from each other on each of said cradle means and engageable with the adjacent wheel for rotating the wheel while so supported, a frame extending across and above the associated rails and having each of its ends projecting beyond the adjacent rail, a motor driven grinding assembly including a grinding wheel positioned on each of the projecting ends of said frame and engageable with the rim of the adjacent car wheel, rollable means for mounting said frame on a support for universal movement on the latter whereby said frame can move relative to said cradle means and the car wheels in response to out-of-roundness of the car wheels, and centering means comprising fixed arms on said frame having car-wheel-engaging means arranged to maintain axial alignment with the wheels despite any out-of-roundness therein whereby said grinding wheels are held at set distances from the centers of the wheels and in grinding engagement with the rims of the car wheels despite an out-of-round condition of the car wheel rims.

4. A cradle for elevating a car wheel above a rail and returning the car wheel to rest upon the rail, comprising two longitudinally-spaced boxes having laterally-spaced members to straddle a rail and rest upon rail flanges, set screws in

said spaced members for clampably engaging opposite sides of the web of a rail beneath the head thereof, longitudinal bolts extending through portions of said laterally-spaced members and between said boxes, wheel-rim-engaging rollers on said boxes, and nuts on said bolts engaging the outer ends of said laterally-spaced portions for drawing said boxes toward each other under circumferentially-spaced portions of the rim of the car wheel, said nuts being arranged to be backed off to permit the weight of the car wheel to separate said rollers and restore the wheel rim upon the head of the rail.

5. A cradle for elevating a car wheel above a rail and returning the car wheel to rest upon the rail, comprising two longitudinally-spaced boxes having laterally-spaced members to straddle a rail and rest upon rail flanges, set screws in said spaced members for clampably engaging opposite sides of the web of a rail beneath the head thereof, longitudinal bolts extending through portions of said laterally-spaced members and between said boxes, wheel-rim-engaging rollers on said boxes, and nuts on said bolts engaging

the outer ends of said laterally-spaced portions for drawing said boxes toward each other under circumferentially-spaced portions of the rims of the car wheel, said nuts being arranged to be backed off to permit the weight of the car wheel to separate said rollers and restore the wheel rim upon the head of the rail, one of said rollers having an axle extending beyond one of said laterally-spaced members and formed for operative connection to driving means for rotating said one roller.
